United States Patent Office

Des. 175,520
Patented Sept. 6, 1955

175,520

HUMIDIFIER UNIT

Milton A. Powers and Robert C. Champlin, Detroit,
Mich., assignors to Skuttle Manufacturing Company,
Milford, Mich., a corporation of Michigan

Application June 17, 1954, Serial No. 31,032

Term of patent 14 years

(Cl. D62—4)

FIG. 1

FIG. 2

FIG. 3

Figure 1 is a front elevation of a humidifier unit embodying our new design;

Figure 2 is a left side elevation of the humidifier unit shown in Figure 1;

Figure 3 is a right side elevation of the humidifier unit shown in Figure 1;

Figure 4 is a plan of the aforesaid humidifier unit;

Figure 5 is a rear elevation of the aforesaid humidifier unit; and

Figure 6 is a bottom view of the aforesaid humidifier unit.

The essential features of our design reside in the portions shown in full lines.

We claim:

The ornamental design for a humidifier unit, as shown and described.
